UNITED STATES PATENT OFFICE

KARL TORSTEN RAGNAR LUNDGREN, OF LUND, SWEDEN

APPARATUS FOR THE PRECIPITATION OF PARTICLES SUSPENDED IN LIQUIDS

Application filed December 16, 1927, Serial No. 240,609, and in Sweden December 22, 1926.

The present invention refers to such apparatus for the precipitation of particles suspended in a liquid, in which the centrifugal force serves as a precipitating force, and which apparatus consists of holders for pipes attached to a rotary shaft, said pipes being adapted to receive the particles in suspension to be precipitated.

In apparatus of this type as hitherto known, the holders carrying the pipes have been so arranged that the longitudinal axis of the pipes would extend at right angles or substantially at right angles to the axis of rotation. This results in that very high speeds of rotation have to be used, in order that any appreciable centrifugal effects shall be attained at all, and these high speeds, in turn, involve, first, that the apparatus must be constructed very sturdy, and, second, that the motor driving the apparatus must be built for a comparatively high output, which all entails a considerable cost of manufacture.

The present invention has for its object to avoid the above mentioned disadvantages, and to bring about a considerably increased centrifugal effect at relatively low speeds of rotation, so that the apparatus can be built lighter while the output of the motor is reduced at the same time.

Moreover, the invention has for its object to facilitate a controllable adjustment of the rate of precipitation, the invention referring primarily to a construction adapted for controllable adjustment of the said rate in blood tests for medical use, but obviously the invention may also be adapted to a controllable adjustment of the rate of precipitation of any particles suspended in a liquid.

The invention substantially consists in that the holders for the precipitation pipes secured to the shaft of the apparatus are so arranged that the longitudinal axis of the pipes form an acute angle with the axis of rotation of such a number of degrees (preferably between 0 and 60°) that a high centrifugal effect is obtained in comparison with the known apparatus where the axis of the pipes forms a right or substantially right angle with the axis of the apparatus. The said holders may then preferably be adapted to receive flattened

pipes in a position where the greater pipe diameter extends either tangentially or radially in relation to the circle described by the pipe at the rotation thereof. Furthermore, the holders carrying the pipes may preferably be adjustably connected to the shaft of the apparatus, so that the angle of inclination may be altered, a controllable rate of precipitation being thus obtained.

The accompanying drawings illustrate some embodiments of an apparatus according to the invention.

Fig. 1 is an axial section of an apparatus according to the one form of embodiment, and Fig. 2 is a top view thereof. Fig. 3 is a top view of a somewhat modified apparatus. Fig. 4 is a side view of an apparatus according to a further modification, and Fig. 5 is a top view thereof.

Referring first to Figs. 1 and 2, 1 designates the housing of an electric motor, to the vertical shaft 2 of which is secured a hub 3, the top portion of which forms a circular disk 4. Secured to said disk 4 is by means of screws 5 the top part of a conical shell or casing 6, to the lower or base end of which is secured a strengthening metal ring 7 having an angular cross-section. Inserted between the said disk 4 and the said ring 7 and substantially parallel to the inclined wall of the casing 6 are metal pipes 8 forming holders for glass pipes 9, in which the precipitation takes place when the casing 6 with the holders 8 and the glass pipes 9 is put in rotation by the motor 1. As visible, particularly from Fig. 2, the pipes 8 and 9 have an elliptical cross-section, the greater or main axis of which extends tangentially to the circular path of the pipes.

The embodiment shown in Fig. 3 differs from that above described in this respect only that the holder pipes 8 and thus also the glass pipes to be inserted therein are located with the main axis of the cross-section substantially radially to the path of movement of the pipes.

In the form of embodiment shown in Figs. 4 and 5, 2 designates a motor shaft (or a manually driven shaft) having a hub 10 secured thereto, said hub carrying a cruciform cross

head 11. Pivots secured to the arms of said cross head are cylindrical holders 12 for glass pipes (not shown), said holders having diametrically opposed strengthening wings 13. Turnably secured to the upper wings 13 of said holders are lugs 14 having transverse threaded bores for substantially diametrically disposed adjusting screw bolts 15, the ends of which are threaded in opposite directions and screwed into the lugs 14 of the oppositely located pairs of holders 12, there being two screw bolts 15 for each of said pairs. By turning said screws, the inclination of the holders 12 may be altered within the desired limits. The holders 12 may of course be flattened similarly to the holders 8 of Figs. 1, 2 and 3.

Now, if the holders 12 with the glass pipes to be inserted therein are adjusted by means of the screws 15 under an acute angle to the axis of rotation (corresponding, for instance, to about 30°), it will be found that the rate of precipitation will be considerably greater than when the pipes extend radially or substantially so with respect to the axis of rotation, as has hitherto been the case.

Investigations carried out have shown that the said increase of the rate of precipitation is determined with respect to its magnitude, first, by the diameter of the pipe, second, by the length of the pipe, and third, by the angle of inclination of the pipe to the axis of rotation, said increase being further determined so that the magnitude of the rate of precipitation will then primarily be dependent on the horizontal distance $d_1 - e_1$ from the free liquid level to the vertical plane cutting the bottom surface of the pipe, as well as on the horizontal distance $f_1 - g_1$ from the upper side of the inclined pipe to the lower side thereof, that is to say, the rate of precipitation is increased on an increase of the height of the liquid column in the pipe, and decreased on an increase of the distance $f_1 - g_1$. The distance $d_1 - e_1$ is influenced, partly by the length of the pipe and partly by its angle of inclination. The distance $f_1 - g_1$ is influenced, partly by the angle of inclination of the pipe, and partly by the length of the diameter of the pipe at right angles to the plane of inclination. On the other hand, the pipe diameter parallel to the plane of inclination apparently does not alter the rate of precipitation in any appreciable degree, for which reason the pipe may be made flat, without the rate of precipitation being altered thereby. Thus the advantage is obtained that the volume of the pipes may be altered within certain limits while maintaining the rate of precipitation.

If it is only desired to obtain a centrifugation of the suspended particles as rapid and complete as possible, the longitudinal axis of the pipe is disposed approximately parallel to the axis of rotation and with the great diameter of the pipe extending tangentially

to the circle described by the pipe at the rotation thereof.

What I claim as new and desire to secure by Letters Patent of the United States of America is:—

1. An apparatus for the precipitation of particles suspended in a liquid, comprising a rotatable member, and holders for pipes secured thereto, said pipes being adapted to receive particles in suspension to be precipitated, said holders and the pipes thereon having their axes disposed at an angle not greater than 50° to the axis of rotation of the rotatable member. 70

2. An apparatus for the precipitation of particles suspended in a liquid, comprising a rotatable member, and holders for pipes secured thereto, said pipes being adapted to receive particles in suspension to be precipitated, said holders and the pipes thereon having their axes disposed at an angle not greater than 50° to the axis of rotation of the rotatable member, and said holders being further arranged to receive flattened pipes in a position where the greater pipe diameter extends tangentially to the circle described by the pipe at the rotation thereof. 80

3. An apparatus for the precipitation of particles suspended in a liquid, comprising a rotatable member, and holders for pipes secured thereto, said pipes being adapted to receive particles in suspension to be precipitated, said holders and the pipes thereon having their axes disposed at an angle not greater than 50° to the axis of rotation of the rotatable member, and said holders being further connected to said rotary member adjustably into fixed positions, so that the angle of inclination of the pipes may be altered. 90

4. An apparatus for the precipitation of particles suspended in a liquid, comprising a rotatable member, and holders for pipes secured thereto, said pipes being adapted to receive particles in suspension to be precipitated, said holders and the pipes thereon having their axes disposed at an angle not greater than 50° to the axis of rotation of the rotatable member, and said holders being further arranged to receive flattened pipes in a position where the greater pipe diameter extends tangentially to the circle described by the pipe at the rotation thereof and being connected to said rotary member in adjustable but fixed positions, so that the angle of inclination of the pipes may be altered. 100

In testimony whereof I affix my signature.

KARL TORSTEN RAGNAR LUNDGREN.
